UNITED STATES PATENT OFFICE.

AMOS E. TULLIS, OF FARGO, NORTH DAKOTA.

ARTIFICIAL LIMB.

1,117,725.

Specification of Letters Patent. Patented Nov. 17, 1914.

Application filed August 4, 1914. Serial No. 854,905.

To all whom it may concern:

Be it known that I, AMOS E. TULLIS, a citizen of the United States, and a resident of Fargo, in the county of Cass and State of North Dakota, have invented certain new and useful Improvements in Artificial Limbs, of which the following is a specification.

My invention relates to artificial limbs, particularly to the means for cushioning the stump of a limb within the artificial limb, and the main object thereof is to provide an air-inflated socket at the stump opening, which is continuous entirely around the said stump, which is readily inflated and deflated without removal from the artificial limb, and which is readily removable from the limb for repair, substitution, or other reasons.

My invention is fully described in the following specification, of which the accompanying drawings form a part, in which the separate parts are designated by the same reference characters in each of the views, and in which:—

25. Figure 1 is a side elevation of an artificial leg constructed in accordance with my present invention; Fig. 2 is a section taken on the line 2—2 of Fig. 1; Fig. 3 is a detached, plan, view of the air-socket which I employ, so and Fig. 4 is an enlarged section taken on the line 4—4 of Fig. 3.

In the drawings forming a part of this application I have shown a shell 5 of an artificial leg provided with an articulating 35 foot 6, said shell being open at its top and provided with an interior, dependent, curtain 7, the lower end of which is entirely free, said curtain being composed of suitable material, such as fabric, chamois, raw-hide, 40 leather, or the like, and being adapted to be easily drawn from the shell and turned downwardly on the exterior surface thereof, there being no vertical seam to connect the side edges or ends, whereby this reversing 45 of the curtain is made possible.

Also stitched, or otherwise secured, to the upper edge of the shell, between the interior surface thereof and the curtain 7, are two dependent sleeves 8 and 9, the lower edges 50 of which may be stitched together but not connected in any manner with the shell 5, whereby the pocket so formed may be turned upwardly and outwardly of the shell to give ready access to the stitching, these sleeves 55 being composed of any suitable material which permits of the above reversal, and the

exteriorly located sleeve, with the parts in operative position, is provided with a hole 10 therethrough in the position of a similar hole 11 through the shell 5, and a recess 12 is also formed in the outer surface of the shell around the hole 11.

Pivots connected with the shell 5, at 13, is a dependent spring plate 14 which is adapted to cover the hole 11 and recess 12, and is provided with a small knob 15 at its lower end which is adapted to enter a hole 16 in a fixed plate 17, whereby said plate 14 is locked in its recess covering position, this being a readily operable covering, although I do not confine myself to any specific form thereof.

The main feature of the invention consists of an endless air-cushion 18, shown in Fig. 3, in plan, and in cross-section in Fig. 2, 75 said air-cushion being preferably composed of rubber and provided with a nipple 19, having a ring 20 around the same, which ring carries a screw-threaded rod 21 along which a plate 22 is adjustably slid by means of a thumb-nut 23 to compress the nipple 19 and thus imprison the air in the cushion 18, said nipple being of flexible material and, preferably, integral with the cushion, and said nipple passes through the openings 35 or holes 10 and 11, after which it is bent downwardly to rest within the recess 12, as does also the sealing plate 22 and connected parts, and are protected thereat by means of the plate 14, and it will be seen 20 that, by moving the said plate 14 out of the way, access is had to the nipple 19 and its sealing means for inflation or deflation of the cushion 18.

To place the air-cushion in position, the 35 curtain 7 is turned upwardly out of the shell and downwardly over the outside thereof, after which the sleeves 8 and 9 are drawn upwardly out of the shell and the air-cushion 18 arranged between the same 100 with the nipple 19 passed through the hole 10 and the free edges of the said sleeves, now above the air-cushion, may now be stitched or otherwise connected together: when so connected, the sleeves 8 and 9, now 105 constituting a pocket for the cushion 18, may be turned downwardly into the shell, the nipple passed through the hole 11, the curtain returned to normal position, the cushion inflated, the nipple sealed, and the covering plate 14 arranged thereover, and the device 110 is ready for use, and it will be seen that

removal of the air-cushion, for substitution or repair, is just as readily accomplished.

It will be further noted that, because of the position of the cushion pocket so formed, the cushion may be positioned at substantially the extreme top of the shell, and this is a great advantage as it operates for the comfort of the wearer, the main feature being, however, the uninterrupted air socket formed by the endless cushion, and the next important feature being the ease of installing or removing the air-cushion, this permitting the unfortunate wearer to himself substitute another cushion for a damaged one, an extra cushion being provided with each limb sold, and thereby continue the use of the limb while the damaged cushion is being repaired.

My invention is very simple, but thoroughly efficient, very comfortable for the wearer, and no more costly than those heretofore vended and, while I have shown and described certain specific details of construction, it will be obvious that modifications thereover may be made, within the scope of the following claims, and with such reservation to myself, it will be seen that the invention consists primarily of the continuous air-socket, the movable pocket there-

for, and the accessible means for forming said pocket, and for inflating said socket.

Having fully described my invention, what I claim as new, and desire to secure by Letters Patent, is:

1. An artificial limb, comprising a shell 35 open at its top, an endless air socket for cushioning the stump of a human limb, means for inflating said socket, and a pocket for said socket secured at the open end of said shell and adapted to be withdrawn 40 from said shell, with said socket.

2. An artificial limb, comprising a shell open at its top, an endless air socket for cushioning the stump of a human limb, 45 means for inflating said socket, two dependent sleeves within said shell and secured at said open top, one on each side of said socket, and means for securing the lower edges of said sleeves together, the pocket so formed being adapted to be bodily withdrawn from said shell, with said socket.

In testimony whereof I have signed my name to this specification in the presence of the subscribing witnesses.

AMOS E. TULLIS.
